Letters Patent No 885, Dated May 5th 1857.

The schedule referred to in the Letters Patent and making part of the same.

2

Wes. 885

To all whom it may concern:

Be it known that we, Jacob Steffe, James Horton, and John Evans, all of the City and County of Philadelphia, and State of Pennsylvania, have produced a new and original Cook Stove design - which we designate as the "Union Complete." and we do hereby declare that the following is a full, clear, and exact description of the same; reference being had to the annexed drawing, forming part of this specification, in which

Figure 1, is a side view of the stove.

Figure 2, is a view of back plate.

Figure 3, is a front elevation of the stove.

Figure 4, is a view showing back foot.

Figure 5, is a view showing front foot.

Similar characters of reference in the several figures denote the same part of stove and design.

Symmetrical figures constituting portions of the ornamental design have but half of the details shown.

The side plate A, has two panels B and C, raised above its surface by mouldings D and E, and is ornamented above handle C, by the figure F, in bas-relief. Above panel B, is the inscription "J. H. L. Smith, Philadelphia" in raised capitals.

The panel B, is ornamented by a figure made up of shell a, scrolls b, central projection c, foliage d, and bands e, arranged and having the configuration set forth in figure 1.

Panel C, bears an ornament made up of central figure f, bands g, and scrolls h, arranged as shown in the drawing.

The back plate G, has an enclosed panel embellished with an ornament made up of a central figure H, in the form of a crop, around which is foliage i; the arrangement and configuration being as shown in figure 2.

The upper front plate I, extends at its ends, over the side plate A, and has its projecting edges ornamented with scrolls j, and foliage k, arranged and configured as shown in figure 3.

The plate is embellished with an ornament

made up of a shell *t*, scrolls *m*, bands *n*, and central projection *o*; above which is a sweeping band *p*, with foliage *q*; the design, configuration and arrangement of these several parts being as shown in figure 3.

The rounded corners of the lower front plate *t*, bear ornaments *K*, and the inclined door *I*, bears an ornament made up of shell central figures *r*, with scrolls *s*, and foliage *t*, sweeping therefrom, the arrangement being as shown in figure 3.

The lower doors *P*, have mouldings *o*, and have each a shell ornament *t*, upon the panel, the design and configuration of which is set forth in figure 3.

The base plate *M*, is ornamented on its edge with figures *w*, and has in each front corner the inscription "Union Complete" in raised capitals.

The back foot *R*, has scrolls *a*, crooked by a beak *b*, and terminates in scrolls *c*; the configuration of this part is set forth in figure 4.

The front foot *R'*, has a central projection *d*, side figures *e*, and terminates at bottom in scrolls *f*; the configuration being as shown in figure 5.

What we claim as new and of our own production is the design, configuration and arrangement of the ornaments upon the several plates and castings, as herein described and set forth in the accompanying drawings, constituting the design of cook stove "Union Complete."

In Testimony whereof, we have hereunto signed our names before two subscribing witnesses.
